UNITED STATES PATENT OFFICE.

JOHN EDWARD ROTHWELL, OF BUTTE, MONTANA, ASSIGNOR TO COLORADO IRON WORKS COMPANY, OF DENVER, COLORADO, A CORPORATION OF MAINE.

APPARATUS FOR THICKENING PULPS.

1,099,396.

Specification of Letters Patent.

Patented June 9, 1914.

Application filed September 18, 1913. Serial No. 790,531.

To all whom it may concern:

Be it known that I, JOHN EDWARD ROTHWELL, a subject of the King of Great Britain, residing at Butte, Montana, have invented 5 certain new and useful Improvements in Apparatus for Thickening Pulps, of which the following is a specification.

My invention relates to apparatus for thickening pulps, and consists in improved 10 means for withdrawing the thickened product.

In heretofore existing apparatus for thickening pulps, of which I am aware, it is impossible to withdraw a uniformly thick 15 product, and this defect has a serious adverse influence on the subsequent treatment.

To obtain a pulp of high density, depth is necessary, and it is customary to make the bottom of the thickening vessel in the form 20 of an inverted cone, the pulp discharge being at the bottom. The solids, instead of flowing evenly down to the opening, adhere to the inner surface of the cone with great tenacity and build up in thickness until there

25 is only a small central space in which the pulp continues moving to the point of discharge. This results in the settling efficiency of the cone being greatly reduced and in the loss of the value of the cone as a storage 30 vessel for thickened pulp. No agitating means has thus far been provided which

35 does not have the effect of reducing the density of the pulp, and attempts to break up the caked pulp result in the dislodged masses clogging the opening. Even with pulps 40 which are of such a nature as to have a tendency to slide down the sides of the cone, such movement is irregular, resulting in surges which greatly disturb the desired

45 action and cause the pulp discharge to be very irregular in density. To overcome this defect and enable the withdrawal of a thick pulp of uniform density, I provide means whereby a circuit of circulating dense pulp

50 is maintained within the cone, the withdrawal being from this circuit. At the same time considerable storage capacity is secured in the cone, a result very desirable but not heretofore attainable practically, for the reason set forth.

My invention comprises a hollow cylinder, open top and bottom, suspended vertically within the thickening vessel in such manner that the top is above the pulp level and the

bottom extends well down into the cone. 55 Within this cylindrical partition is an air lift adapted to raise the pulp from a point near the bottom of the vessel to a point above the top of the partition. Above the partition is a small receptacle to receive the 60 pulp from the air lift. This receptacle is provided with suitable outlets, from which the pulp is led for treatment and also with outlets for returning any excess to the interior of the cylinder. The air lift is op- 65 erated at a capacity in excess of that required for the withdrawal of the desired amount of pulp and it is this excess, circulated through the cylinder and air lift, which maintains the solids in motion and 70 prevents the adhesion of thickened pulp to the sides of the tank.

In order that my invention may be readily understood by those skilled in the art, I have appended hereto a sheet of drawings in 75 which the figure is a sectional elevation of an apparatus embodying my invention. In this, 1 is a settling tank, circular in plan with a cone bottom and to which the material to be operated upon is delivered 80 through the launder 2. Centrally within this tank is a hollow cylinder 3, of such length and so sustained that its top will be above the level of the material in the tank and its bottom submerged rather deeply. 85 Within this cylinder is a pipe 4, the lower open end of which is close to the apex of the cone and whose upper end opens into a receptacle 5, situated above the cylinder. The pipe 4, with the inner pipe 6, form an air 90 lift adapted to raise the densest pulp from the apex of the cone to the receptacle 5. The receptacle 5 is provided with suitable outlets susceptible of adjustment, molasses gates for example, as shown at 7 and 8. At 9, is 95 shown a launder encircling the upper edge of the tank for the purpose of catching the clear liquid which overflows, and 10 is an outlet in this launder.

In operation, a mixture of fine solids sus- 100 pended in liquid is fed continuously to the tank 1, as by the launder 2, the solids sub- siding and the clear liquid overflowing the rim of the tank into the launder 9. The clear liquid thus collected is drawn from 105 this launder through the opening 10 and is carried off by the launder 11. The air lift, formed by the pipes 4 and 6, continu-

ously elevates the thickened pulp from the apex of the cone, delivering it into the receptacle 5, from which a part of it is continuously drawn for use through the outlet 7 into the launder 12. The air lift is operated at a greater capacity than necessary to supply the amount withdrawn through 7, and the excess is returned to the interior of the cylinder through other openings, one 10 of which is indicated at 8. By this means the thick pulp is kept in circulation and prevented from settling hard and the entire mass occupying the lower portion of the cone and the interior of the cylinder is 15 maintained of a substantially uniform density. Fluctuations in the liquid content of the pulp withdrawn through 7 are avoided, subsequent treatment of the product is facilitated, and control of the operation made 20 easy. In practice, the difference in level between the surface 14, of the pulp in the cylinder and the surface 15, of the liquid in the body of the tank forms an efficient index of the density of the pulp being withdrawn. The upper end of the air pipe 6 is 25 connected to the air supply by a hose 13, so that if it is desired to agitate the pulp in the lower part of the cone, the pipe 6 may be lowered till it is below the orifice 30 of the pump column 4, when the escaping air will rise upward outside of the pipe 4. When the pipe 6 is again raised so that its end is within the pipe 4, the air rises through the latter and the combination operates 35 as an air lift. In operation a quite dense pulp is carried in the cone to a point above the lower edge of the cylinder 8, and the quiet settling conditions of the upper portion of the tank are not disturbed. 40 While I show my improvement in connection with a simple cone, it is equally well adapted to use with other apparatus such as pulp storage tanks or with sloughing off tanks for use in concentration, overflowing 45 the slime and supplying a uniform pulp to the tables. An application of great importance is to continuous decantation as practised in the cyanid process. In this a very essential condition to satisfactory operation is the ability to draw a thick pulp 50 of uniform density from each of the decantation vessels.

My invention is susceptible of variation as to the form of the parts and nature of the 55 elements used as means to accomplish the desired ends as well as to the kind of tank or other vessel to which it is applied, the essence of my invention residing in means for maintaining a thick pulp in such a state 60 of motion as to prevent its thickening to an undesirable degree and to enable the withdrawal of a thick pulp of uniform density. Thus, I contemplate raising the thick pulp 65 from the apex of the cone to the receptacle 5 by any means suitable for handling the

particular material operated upon, a diaphragm pump for example being preferable under certain conditions (as where an air lift would cause excessive foaming or where compressed air was not available). 70

What I claim is:

1. In combination a tank for thickening pulps, means for withdrawing the thickened pulp comprising a receptacle placed above the tank, a partition within the tank, a pump for raising the thickened pulp from the bottom of the tank to the receptacle and outlets from the receptacle adapted to deliver a portion of the pulp for use and to return the excess to the interior of the partition. 75
2. In combination a tank for thickening pulps, means for withdrawing the thickened pulp consisting in a receptacle placed above the tank, a partition within the tank, an air lift for raising the thickened pulp from the bottom of the tank to the receptacle and outlets from the receptacle adapted to deliver a portion of the pulp for use and to return the excess to the interior of the partition. 85
3. In combination a tank for thickening pulps, means for withdrawing the thickened pulp consisting in a receptacle placed above the tank, a partition within the tank, an air lift with a vertically adjustable air pipe for raising the thickened pulp from the bottom of the tank to the receptacle and outlets from the receptacle adapted to deliver a portion of the pulp for use and to return the excess to the interior of the partition. 95
4. In combination a tank for thickening pulps, means for withdrawing the thickened pulp consisting in a receptacle placed above the tank, a partition within the tank, a pump for raising the thickened pulp from the bottom of the tank to the receptacle and adjustable outlets from the receptacle adapted to deliver a portion of the pulp for use and to return the excess to the interior of the partition. 105
5. In combination a tank for thickening pulps, means for withdrawing the thickened pulp consisting in a receptacle placed above the tank, a partition within the tank, an air lift for raising the thickened pulp from the bottom of the tank to the receptacle and adjustable outlets from the receptacle adapted to deliver a portion of the pulp for use and to return the excess to the interior of the partition. 115
6. In combination a tank for thickening pulps, means for withdrawing the thickened pulp consisting in a receptacle placed above the tank, a partition within the tank, an air lift with a vertically adjustable air pipe for raising the thickened pulp from the bottom of the tank to the receptacle and adjustable outlets from the receptacle adapted to deliver a portion of the pulp for use and to return the excess to the interior of the partition. 125

liver a portion of the pulp for use and to return the excess to the interior of the partition.

7. In apparatus of the class described, a tank, a receptacle above the tank, a pump adapted to raise thick pulp from the bottom of the tank to the receptacle, one or more outlets in the receptacle for withdrawing a portion of said pulp and means for returning the excess pulp to the tank at a point near the bottom.

8. In apparatus of the class described, a tank, a receptacle above the tank, an air lift adapted to raise thick pulp from the bottom 15 of the tank to the receptacle, one or more outlets in the receptacle for withdrawing a portion of said pulp and means for return-

ing the excess pulp to the tank at a point near the bottom.

9. In apparatus of the class described, a tank, a receptacle above the tank, an air lift with a vertically adjustable air pipe adapted to raise thick pulp from the bottom of the tank to the receptacle, one or more outlets 20 in the receptacle for withdrawing a portion of said pulp and means for returning the excess pulp to the tank at a point near the bottom.

In testimony whereof, I affix my signature in presence of two witnesses.

JOHN EDWARD ROTHWELL.
